UNITED STATES PATENT OFFICE.

ISER P. COHEN, OF NEW YORK, N. Y.

DESIGN FOR A KNITTED BLOUSE.

Application filed March 20, 1925. Serial No. 12,781. Term of patent 3½ years.

To all whom it may concern:

Be it known that I, ISER P. COHEN, a citizen of the United States, residing in the city of New York, borough of Manhattan, county and State of New York, have invented a new, original, and ornamental Design for Knitted Blouse, of which the following is a specification, reference being had to the accompanying drawing, forming part thereof.

The figure is a view in elevation of a knitted blouse, showing my new design.

I claim:

The ornamental design for a knitted blouse as shown.

ISER P. COHEN.
